APPARATUS FOR SECURING BAG BOTTOMS

Edward Jaeger, New York, N. Y., assignor to
 Oneida Paper Products, Inc., New York, N. Y.,
 a corporation of New York

Application April 12, 1938, Serial No. 201,529

14 Claims. (Cl. 93—8)

My invention relates to an apparatus and method for securing, by an added operation, the pasted flaps of the bottom of a folded bottom bag. More specifically my invention relates to an apparatus for pressing on the folded bottoms of bags as they are delivered on to the delivery belt, the apparatus having a flopping motion and a sideways motion that moves with the moving bags.

10 Great difficulty has been experienced in the manufacture of bags with bottoms that are formed by pasting down the flaps on a folded bottom because of the fact that the flaps tend to separate from the bag bottoms while the paste is still undried and consequently imperfect bags are formed. Since it is impossible to economically repaste the bottoms of these bags, they constitute rejects. Although a small percentage of bags come through the machine with the flaps 15 unsecured, there is a serious loss incumbent in these rejects.

20 I have devised a novel apparatus which acts upon the bags directly as they are delivered from the forming machine on to the delivery apparatus. This apparatus has remedied completely the difficulty of separated or unpasted bottom flaps. Specifically, I provide a plate that is so actuated and timed with the bag forming machine as to move down upon the bag bottoms as the bags come out of the forming machine and press the bottoms so as to secure firmly bonded flap and bottom engagement.

25 Preferably, the plate is further actuated so as to move in the direction of the travel of the bags so as to provide no stoppage to the automatic and continuous delivery of bags. By means of a novel arrangement of drive and cam engagements, this desirable pressing effect is obtained.

30 It is the object of my invention to provide a novel apparatus for synchronously pressing folded and pasted bag bottoms as the bags emerge 35 from the forming machine.

35 It is another object of my invention to provide a novel plate apparatus synchronously timed with the forming machine that acts by means of a cam to press the bag bottoms at that point where a loosening of engagement of the bag flaps with the bag bottom may occur.

40 It is a further object of my invention to provide a novel apparatus comprising a plate which moves down upon the bag bottoms and at the same time moves in the direction of travel of the bags.

45 Other objects of my invention will be apparent

from the drawing and the description of the operation which follows.

Figure 1 represents a perspective view of the apparatus of my invention.

Figure 2 represents a cross section taken along the line 2—2 of Figure 1 as the plate prepares to descend upon a bag whose flaps have separated from the bag bottom. 5

Figure 3 represents a cross section taken along the same line 2—2 in which the plate has descended and pressed down the flaps of the bag bottom upon the bag. 10

Referring now more specifically to the drawing, in Figure 1 I show a drive shaft 1 terminating in a bevel gear 2 which coacts with a similar bevel gear 3 mounted on a shaft 4 carried by the bearing 5. Rigidly mounted on the shaft 4 is a split cam 6 with the two sections 7 and 8 which are joined through the slot 9 by means of the screw 10. By means of this split cam arrangement a 20 cam surface of the desired length may be had. Thus, by adjustment of the two sections 7 and 8 of the cam by means of the slot and screw arrangement a greater or lesser cam surface may be provided. The split cam 6 acts on rotation 25 upon a roller 11 rotatably mounted on an arm 12. The arm 12 and the arm 13 are rigid with respect to each other and are mounted for rotation in the bearing 14. A spring 15 acts to draw the arm 12 down against the cam 6. The bearing 14 may 30 be a cast piece and can be secured by means of the plate 16 on to a suitable surface.

The arm 13 terminates in an engaging member 17 which engages the link 18. The link 18 rides in a slot 19 in a block 20. This positioning 35 of the link in a slot prevents a sideways motion of the link 18. The link 18 is secured at 23 to the shaft 24 mounted in the bearings 25 and 26 which constitute a portion of the brackets 27 and 28. The brackets 27 and 28 are securely mounted by means of the fastening means 30 to the plate 31.

Returning now to the driven shaft 4, it is found that the shaft is mounted in the bearing 40. At the end of the shaft there is rigidly mounted 45 thereon a cam 41 with a cam surface 42. This cam surface acts on rotation with the roller 43 mounted by means of the pin 44 on the arm 45. Rigid with the arm 45 is an arm 46. Arms 45 and 46 are mounted to rotate about the rigid 50 shaft 47 mounted in the bearing 48 secured by the bracket 49 to a suitable surface. A spring 50 secured to the arm 46 at 51 pulls the arm 46 so as to maintain the roller 43 against the cam surface 42.

The arm 46 terminates in a forked member 57 where it is engaged with a link 58 by means of a pin 59. The link 58 engages, by means of the pin 60, a bracket 61 which is rigidly mounted 5 upon the shaft 62 by means of a suitable securing means. The shaft 62 is loosely mounted in the bearings 70 and 71 so that it can move freely back and forth through these bearings under the pull of the bracket 61. The bearings 70 and 71 10 are secured by means of the flanges 72 and 73 to a suitable surface. The plate 31 is secured for rotation with the shaft 62 by means of the brackets 74 and 75. The plate 31 is adapted to move down upon the bags 80 which are delivered in the direction shown by the arrow 81 15 onto the delivery belt 82. This delivery belt is maintained as a fairly rigid surface to support the pressure plate 31 by making the delivery belt of metallic material as in sections or by providing suitable supporting surfaces 85 thereunder. The delivery belt is adapted to move about the drums 90 and 91 which rotate about the shafts 92 and 93, the shafts being driven by a suitable power source.

25 Referring now more specifically to Figure 2, there is shown a bag 80 upon the delivery belt 82 with the bottom flap 100 separated from the bag bottom. The delivery belt rides over a rigid supporting surface 85. Positioned to move down 30 upon and press the bag flap upon the bag bottom is the plate 31 actuated by the link 18.

The operation of the apparatus will now be described. As has been noted above, as the bag 80 comes from the bag forming machine there is 35 often a tendency for the flap 100 to separate from the bag. It is very desirable to prevent this separation and for that purpose the plate 31 moves down upon the bag bottoms as the bags ride on the delivery belt, and repeatedly presses the 40 flaps down upon the bag bottoms. In order not to interrupt the continuous motion of the bags, in addition to the downward flopping motion of the plate 31, a sidewise travel in the direction of travel of the bags is provided for this plate.

45 It is imperative that the action of the plate 31 be synchronized with the formation of the bags and their delivery from the machine on to the delivery belt. In order to effect this synchronization the drive for the apparatus of my invention 50 is provided through the shaft 1 which is connected with the drive mechanism for the bag forming machine itself. The drive 1 acts through the bevel gears 2 and 3 to rotate the shaft 4. The split cam 6 is so adjusted as to provide a 55 suitable cam surface so that the plate 31 is pressed down upon the bags for sufficient time, in accordance with what is necessary to prevent separation of the bag bottoms.

Split cam 6 rotated by the shaft 4 acts against 60 the roller 11 to move the arm 12 against the action of the spring 15. The arm 12 in turn moves the rigidly connected arm 13 which acts through the connecting member 17 on to link 18 throwing that link 18 forward when the high 65 surface of the cam 6 acts upon the roller 11. As the link 18 moves forward through the slot 19 it positions against the surface 24 thus forcing down the plate 31 onto the bags 80 and the possibly detached bag flaps 100. The plate 31 then 70 bears against the bags 80 for the time determined by the extent of the high cam surface on the cam 6. When the low cam surface acts on the roller 11, the spring 15 pulls the arm 12 down to bring the link 18 back consequently lifting 75 the plate 31. In synchronous arrangement with

this vertical movement, a side travel of the plate 31 is provided by means of the cam 41 on the end of the shaft 4 acting against the roller 43 mounted on the arm 45. As the high portion of the cam 42 bears against the roller 43 the arm 45 is forced downwardly and the rigidly connected arm 46 is thereupon thrown to the right against the action of the spring 50. By means of the connection 57 this thrust is transmitted to the link 58 which is connected at 60 to the bracket 61. The bracket 61 being rigidly secured to the shaft 62 moves the shaft to the right and with it the plate 31 which is rigidly secured to the shaft by means of the brackets 74 and 75.

Upon movement of the plate 31, as indicated, 15 the link 18 through the opening 23 rides freely upon the shaft 24. The link 18 is maintained as has been noted against sideways motion by the rigidly secured block 20 and the slot 19 therein.

Thus, as a bag is delivered from the bag forming machine at 81 on to the delivery belt 82, the plate 31 moves down upon the bag and presses it firmly so that any separated flap 100 is resecured to the bag bottom. At the same 25 time that the plate 31 is moved down, it is also moving at a predetermined speed in the direction of travel of the bags so that there is no interruption to the travel of the bags. At the end of its path of travel, the plate is again lifted 30 and returns by reason of the action of the spring 50 against the link 46 and because of the action of the roller portion of the cam 41 against the roller 43. The plate 31 again descends at a pre-determined time and presses both the newly 35 delivered bags and the bags which have just been pressed. Thus the bags as they travel upon the delivery belt are continuously subjected to the pressing action of the plate 31 so that any possibly detached flaps of the bag are resecured. 40

The machines can be used in the manufacture of flat bottom bags, single flap bags, satchel bottom bags, coffee bags and double bottom bags. New and improved results have been secured by the use of this synchronizing mechanism. The 45 problem of separated bag bottoms has been a serious one in the industry and it has been difficult to devise a mechanism which can effect the desired resecuring without interrupting the travel of the bags.

As is evident the split cam 6 is adjusted with respect to the cam 41 so that the proper up and down motion of the plate 31 is effected with respect to the sidewise travel of the plate.

I claim:

1. A bag bottom pressing apparatus comprising a reciprocating plate rigidly attached to and adapted to move with a shaft, said shaft being mounted in bearings, means for moving the plate down upon bags travelling on a delivery belt 60 comprising a link, said link being actuated by an arm, said arm being actuated by a cam mounted on a driven shaft.

2. A bag bottom pressing apparatus comprising a reciprocating plate rigidly attached to and 65 adapted to move with a shaft, said shaft being mounted in bearings, and means for moving the plate down upon bags travelling on a delivery belt comprising a link moving within a slot, said link being actuated by an arm, said arm being actuated by a cam mounted on a driven shaft.

3. A bag bottom pressing apparatus comprising a reciprocating plate and means for moving the plate down upon bags travelling on a delivery belt, and a driven shaft having two cams rigidly 75

affixed thereto for actuating said reciprocating plate in the two movements.

4. A bag bottom pressing apparatus comprising a reciprocating plate rigidly attached to and adapted to move with a shaft, said shaft being mounted in bearings, and means for moving the plate down upon bags travelling on a delivery belt comprising a link moving within a slot, said link being actuated by an arm, said arm being actuated by a cam mounted on a driven shaft to move in timed relation with the bag forming machine which delivers the bags to be pressed.

5. A bag pressing apparatus comprising a supported delivery belt, a reciprocating plate adapted to rotate on a shaft to press freshly pasted bag bottoms, and means for moving the plate down upon bags travelling on a delivery belt comprising a link, said link being actuated by an arm to move in timed relation with the bags to be pressed, said arm being actuated by a cam.

6. A bag pressing apparatus comprising a supported delivery belt, a reciprocating plate adapted to rotate on a shaft to press freshly pasted bag bottoms, and means for moving the plate down upon bags travelling on a delivery belt comprising a link moving within a slot, said link being actuated by an arm to move in timed relation with the bag forming machine which delivers the bags to be pressed, said arm being pivoted about a fixed point, said arm being actuated by a cam.

7. A bag pressing apparatus comprising a supported delivery belt, a reciprocating plate adapted to rotate on a shaft to press freshly pasted bag bottoms, means for moving the plate down upon bags travelling on a delivery belt comprising a link, said link being actuated by an arm, said arm being actuated by a cam mounted on a driven shaft, a second cam mounted to act in timed relation with said first mentioned cam, said second cam being mounted on said driven shaft, said second cam being positioned to actuate an arm, said arm being positioned to actuate a link, said link being positioned to effect a reciprocating sidewise motion of the reciprocating plate.

8. A bag pressing apparatus comprising a supported delivery belt, a reciprocating plate rigidly attached to and adapted to move with a shaft, said shaft being mounted in bearings, said shaft extending a distance on both sides of said bearings, means for moving the plate down upon bags travelling on a delivery belt comprising a link, said link being actuated by an arm, said arm being pivoted about a fixed point, said arm being actuated by a cam mounted on a driven shaft, a second cam mounted to act in timed relation with said first mentioned cam, said second cam being mounted on said driven shaft, said second cam being positioned to actuate an arm, said arm being positioned to actuate a link, said link being connected with a bracket, said bracket being rigidly secured to said first mentioned shaft whereby upon actuation by said second cam said first shaft and rigidly attached pressing plate are moved in sidewise motion in the direction of the bags on the delivery belt.

9. A bag pressing apparatus comprising a supported delivery belt, a reciprocating plate rigidly attached to and adapted to move with a shaft, said shaft being mounted in bearings, said shaft extending a distance on both sides of said bearings, means for moving the plate down upon bags travelling on a delivery belt comprising a link moving within a slot, said link being actuated by an arm, said arm being pivoted about a fixed

point, said arm being actuated by a cam mounted on a driven shaft, a second cam mounted to act in timed relation with said first mentioned cam, said second cam being mounted on said driven shaft, said second cam being positioned to actuate an arm, said arm being pivoted about a fixed point, said arm being positioned to actuate a link, said link being connected with a bracket, said bracket being rigidly secured to said first mentioned shaft whereby upon actuation by said second cam said first shaft and rigidly attached pressing plate are moved in sidewise motion in the direction of the bags on the delivery belt.

10. A bag pressing apparatus comprising a supported delivery belt, a reciprocating plate rigidly attached to and adapted to move with a shaft, said shaft being mounted in bearings, said shaft extending a distance on both sides of said bearings, means for moving the plate down upon bags travelling on a delivery belt comprising a link moving within a slot, said link being actuated by an arm, said arm being pivoted about a fixed point, said arm being actuated by a cam mounted on a driven shaft, a second cam mounted to act in timed relation with said first mentioned cam, said second cam being mounted on said driven shaft, said second cam being positioned to actuate an arm, said arm being pivoted about a fixed point, said arm being positioned to actuate a link, said link being connected with a bracket, said bracket being rigidly secured to said first mentioned shaft whereby upon actuation by said second cam said first shaft and rigidly attached pressing plate are moved in sidewise motion in the direction of the bags on the delivery belt.

11. A bag bottom pressing apparatus comprising a reciprocating plate rigidly attached to and adapted to move with a shaft, said shaft being mounted in bearings, and means attached to said shaft for effecting lateral movement of said plate, said last mentioned means comprising a pivoted rocking arm, one end of said arm engaging a link in operative engagement with said shaft, the other end of said arm being actuated by a cam.

12. A bag bottom pressing apparatus comprising a reciprocating plate rigidly attached to and adapted to move with a shaft, said shaft being mounted in bearings, means attached to said shaft for effecting lateral movement of said plate, said last mentioned means comprising a pivoted rocking arm, one end of said arm engaging a link in operative engagement with said shaft, the other end of said arm being actuated by a cam, and means comprising a link for moving the plate down upon bags travelling on a delivery belt.

13. A bag bottom pressing apparatus comprising a reciprocating plate rigidly attached to and adapted to move with a shaft, said shaft being mounted in bearings, and means for moving the plate down upon bags travelling on a delivery belt comprising a link, said link being actuated by an arm; said arm being actuated by an intermittent actuating means.

14. A bag bottom pressing apparatus comprising a supported delivery belt, a reciprocating plate adapted to move with a shaft to press freshly pasted bag bottoms, and means for moving the plate in the direction of travel of the delivery belt when it presses against the delivery belt, and means for retracting the plate from its pressing position and returning it laterally to its original position and means for providing both

movements of the reciprocating plate in timed relation to the delivery of the bags from the bag forming machine, both said reciprocating plate and said means for providing movement of the plate in the direction of travel of the delivery belt being actuated from a common shaft, two

cams mounted on said shaft, rocker arms in contact with said cams, said rocker arms actuating links, said links operating respectively said reciprocating plate and said means for moving the plate in the direction of travel.

EDWARD JAEGER.
